O. SYVERTSEN

ASH PAN

Filed May 26, 1923

FIG. 1

FIG. 2

FIG. 3

FIG. 4

Inventor
Ole Syvertsen

By Clarence Walker
His Attorney

UNITED STATES PATENT OFFICE.

OLE SYVERTSEN, OF JAMESTOWN, NEW YORK, ASSIGNOR OF ONE-HALF TO HERBERT CHIVERTON, OF JAMESTOWN, NEW YORK.

ASH PAN.

Application filed May 26, 1923. Serial No. 641,741.

To all whom it may concern:

Be it known that OLE SYVERTSEN, a citizen of the United States, residing at the city of Jamestown, in the county of Chautauqua and State of New York, has invented certain new and useful Improvements in Ash Pans, of which the following, taken in connection with the accompanying drawings, is a specification.

10 This invention relates to an improvement in ash pans, and more particularly to ash pans intended for use below the grates of house furnaces or boilers for the purpose of catching and collecting the ashes as they fall 15 through the grate.

Ash pans of this general type have been previously made, but they are open to the objection that when used in the ash pit of a furnace or boiler, the draft through the lower door is interfered with and for that reason such pans have not come into common use.

20 The chief object of this invention is to provide an ash pan, the front wall of which is hinged, so that it may be lowered when the pan is in the ash pit, thus permitting the draft from the lower door by which the furnace is commonly regulated, and which is also provided with deflectors adapted to be opened when the ash pan is in the receiving 25 position, thus catching any ashes that might otherwise fall outside the body of the pan, and adapted to be closed when the ash pan is removed.

30 A further object of this invention is to provide in connection with an ash pan of this type a cover which can be applied, after the ash pan has been removed from the pit, to completely enclose the ashes, this cover being so formed, that it will not interfere 35 with the opening of the front wall when the pan has been transferred to the place where the ashes are to be dumped.

40 Another object of this invention is the provision, in the rear wall of the ash pan and in the hinged front wall, of handles by which the pan can easily be manipulated.

45 Other objects of this invention reside in the details of construction set forth in the following specification and in the drawings, 50 which form a part thereof, and in which

Fig. 1 is a front elevation of an ash pan, embodying one form of this invention, installed in the ash pit of a furnace;

Fig. 2 is a similar view of the ash pan

alone with the deflectors and pivoted front 55 wall closed;

Fig. 3 is a side elevation, certain parts being broken away, of the ash pan with the deflectors closed and the front wall open; and

Fig. 4 is a plan view of the ash pan, having the cover applied thereto, the front wall being shown closed, but its open position being indicated by dotted lines.

Referring to the drawings, the reference 65 numeral 10 indicates an ash pan embodying one form of this invention adapted to be installed in the ash pit 11 of a furnace 12. The pan 10 is made of sheet metal comprising a bottom 13, side walls 14 and end wall 15. The end wall 15 is shown curved, because it is customary in furnaces to curve the inner walls of the ash pit, and is preferably made slightly higher than the side walls 14, as shown in the drawings, and inclined rearwardly.

Hinged at the front edge of the bottom 13 is the front wall 16 provided at each side with wings 17, which close the spaces between the sides of the front wall and the 80 side walls 14. In the side walls 14 are provided curved recessed guides 18, which receive the edges of the wings 17.

Hinged upon the upper edges of the side walls 14 are deflector plates 19. These 85 plates are preferably hinged by means of rods 20, fixed to the plates and passing through straps 26 on the side walls. Handles 21 on the rods 20 project beyond the side walls 14 and are turned at right angles 90 thereto, so that they can easily be reached and actuated when it is desired to close the deflector plates.

Removably secured to the top of the rear wall 15 is a handle 22 and rigidly secured to the front wall 16 is a handle 23. These handles are preferably arranged at the longitudinal center of the ash pan so that by their use, the pan, when filled, can easily be raised without tilting. In order to close the pan after it has been filled with ashes and removed from the ash pit and thus prevent the blowing and scattering of ashes before the place of deposit has been reached, a cover 24 is provided. This cover has hooked plates 25 which slip over the upper edges of the rear walls 15, and is flanged at 100 the sides to extend over the side walls 14.

When the pan is being installed in the ash pit, the deflectors 19 and the front wall are closed, as shown in Fig. 2. After it has been placed in the proper position below the grate, the deflector plates 19 are opened by the actuation of the handles 21 until they strike against the side walls of the ash pit 11. The front wall 16 is now opened into the position shown in full lines in Fig. 3, 10 and in dotted lines in Fig. 4, lying on the floor of the box so that there will be no interference with the draft through the lower door of the furnace.

After the pan has become filled with the 15 ashes, the deflector plates are closed and the ash pan is withdrawn from the pit by pulling the handle 23. When entirely removed from the ash pit, the front wall 16 is closed, the handle 22 hooked into the rear wall, and 20 the cover 24 placed upon the pan. The filled pan is then lifted by means of the handles 22 and 23 and carried to the place of deposit where the ashes are dumped by opening the front wall 16 and raising the rear of the 25 pan, the cover remaining in position upon the pan so as to minimize the escape of dust.

Thus, by the use of this invention, the 30 clearing of the ash pit is accomplished without the use of a shovel and without the usual scattering and blowing around of ashes and dust. In case the pan becomes, 35 through neglect, so full that the deflector plates cannot be closed down, the excess is removed by a shovel in the ordinary way. Since the rear wall is inclined, it follows 40 that any small amount of ashes in the pit will not interfere with the location of the pan.

While one embodiment of this invention 45 has been shown and described, I am not to be limited thereto, since it is obvious that

others may be made without departing from the spirit and scope of the invention as set forth in the following claims.

Having thus set forth my invention what 45 I claim as new, and for which I desire protection by Letters Patent is:

1. An ash pan adapted to be installed in the ash pit of a furnace to receive the ashes dropping through the grate and having a 50 hinged front wall adapted to lie normally on the floor of the pit and permit the free passage of draft, said wall being raised when the ash pan is to be removed from the pit, and thus prevent the escape of ashes 55 therefrom.

2. An ash pan adapted to be installed in the ash pit of a furnace to receive the ashes dropping through the grate thereof, and having deflector plates hinged thereto which, 60 when open, rest against the walls of the ash pit and a hinged front wall independent of said deflector plates adapted to lie normally on the floor of the ash pit and permit the 65 free passage of draft.

3. An ash pan adapted to be installed in the ash pit of a furnace to receive the ashes dropping through the grate thereof comprising bottom, side and rear walls, deflector plates, hinged upon said side walls, a 70 front wall hinged to said bottom, wings on said front wall to close the spaces between the sides of the front wall and the side walls, recessed guides in said side walls to receive the edges of said wings, and a removable 75 cover for closing the pan, said cover permitting the raising and lowering of said front wall.

In testimony whereof I have affixed my signature.

OLE SYVERTSEN.
